(57) **CLAIM**

I claim the ornamental design for a lighter holder, as shown and described.

DESCRIPTION

FIG. 1 is a perspective view of a lighter holder showing my new design in connection with a key chain and a lighter, said key chain and lighter forming no part of the claimed design; FIG. 2 is a front-side elevational view thereof, the backside view being a mirror image of the front side;

FIG. 3 is a right-side elevational view thereof, the left side being a mirror image of the right side;

FIG. 4 is a top elevational view thereof; and,

FIG. 5 is a bottom elevational view thereof.
